UNITED STATES PATENT OFFICE

94,380

DESIGN FOR A CHAISE LONGUE

Frank Debski, Brooklyn, N. Y.

Application November 20, 1934, Serial No. 54,085

Term of patent 3½ years

To all whom it may concern:

Be it known that I, Frank Debski, a citizen of the United States, and a resident of Brooklyn, in the county of Kings and State of New York, have invented a new, original, and ornamental Design for a Chaise Longue, of which the following is a specification, reference being had to the accompanying drawing, forming part thereof.

I claim:
The ornamental design for a chaise longue, as shown.

FRANK DEBSKI.
